DESIGN FOR A COMBINED SPRAY GUN AND CONTAINER CAP

Adelbert C. Radtke, Forest Park, Ill., assignor to Sears, Roebuck and Co., Chicago, Ill., a corporation of New York

Application October 3, 1938, Serial No. 80,223

Term of patent 7 years

To all whom it may concern:

Be it known that I, Adelbert C. Radtke, a citizen of the United States, residing at Forest Park, in the county of Cook and State of Illinois, have invented a new, original, and ornamental Design for a Combined Spray Gun and Container Cap, of which the following is a specification, reference being had to the accompanying drawing, forming a part thereof.

The figure is a perspective view of the combined spray gun and container cap embodying my new design. The other side of the design is substantially like the side shown.

I claim:

The ornamental design for a combined spray gun and container cap, substantially as shown and described.

ADELBERT C. RADTKE.
